REGISTER

Lee R. Brown, East Orange, N. J., assignor to
 Monroe Calculating Machine Company, Orange,
 N. J., a corporation of Delaware

Application April 20, 1931, Serial No. 531,274

4 Claims. (Cl. 235—144)

The invention relates to registers, more particularly to resetting means for the dials of registers adapted for special computations.

As illustrated herein, the registration displayed does not consist of the true value of an amount entered in the digit keys or of a product thereof, but includes an arbitrary value in certain dials, whereby for instance a registration is obtained showing even figures only in the cents 5 dials, in making computations in U. S. currency.

This arrangement is particularly useful in certain computations involving tax assessments, wherein the total tax is to be divided into two semi-annual payments, the object of the special 10 arrangement being to avoid inaccuracies involved in eliminating half cents in the semi-annual payment. While, however, the arrangement shown and described relates to means for computing to the nearest even cent or other value, it is obvious that the same mechanism would be useful 15 in registering other arbitrary values, as for instance, in computing tax payments upon the quarter payment plan or in making various computations carried to the nearest half-cent or 20 the nearest five centimes.

In the embodiment of the invention illustrated herein certain mechanisms are employed which are in accordance with the disclosures of U. S. patent application 337,073 filed February 2, 1929 25 by E. F. Britten, Jr. entitled Registering mechanism now Patent No. 1,849,448 (corresponding to French Patent 673,110) and U. S. application 379,948, filed July 2, 1929 by E. F. Britten, Jr. and entitled Calculating machine, now Patent No. 35 1,860,490.

The invention consists in the novel construction and combination of parts as set forth in the appended claims.

In the accompanying drawings, illustrating the 40 invention:

Fig. 1 is a top plan view of a calculating machine embodying the invention, showing the condition of the machine after the sub-total dials have been cleared:

Fig. 2 is a fragmentary bottom plan view showing the resetting mechanism set for normal operation:

Fig. 3 is a similar view showing the mechanism set for even cent operation.

Fig. 4 is a section, taken substantially on line 4—4 Fig. 1.

Fig. 5 is a section, taken substantially on line 5—5 of Fig. 1.

Fig. 6 is a section, taken substantially on line 55 6—6 of Fig. 1.

Fig. 7 shows a planular development of the cents dial of the sub-total register.

Fig. 8 is a similar view, illustrating the cents dial of the grand total register.

The machine illustrated is known on the market as the Monroe calculating machine, disclosed in its essential parts in the Chase Patent 1,566,- 650, to which reference is made for details of machine operation not specifically forming part of the present invention.

Referring to Fig. 1 of the drawings, a line of revolutions counting dials 19 is shown, together with a parallel line of totalizer dials. Each of these totalizer dials may be connected with the adjacent dial by tens carry mechanism, or the line may consist of two series of dials, each series provided with its own tens carry mechanism. In any case, in the special work for which the machine is designed, these dials are used as separate accumulators, separately resettable to clear 75 therefrom accumulated values, and will be referred to hereinafter as sub-total dials and grand total dials respectively. The ten accumulator dials at the right hand of the line are adapted to be reset at each operation of the clearing 80 handle 18, and constitute the sub-total dials, the ten dials at the left hand of the line being cleared only when special mechanism is set for that purpose, and constitute the grand total dials.

An amount to be entered in the sub-total and grand total dials is intended to be set up separately at the right hand and left hand sides of the keyboard 15, but it is to be noted that the present invention is applicable to the machine shown in Patent 1,793,155 issued to E. F. Britten, Jr., on February 17, 1931 and entitled Calculating machine, this patent showing two series of totalizer dials arranged in tandem and a set of digit keys adapted to control the registration of a single selected amount simultaneously in both 95 totalizers. Arranged parallel with the rotation counting and totalizer dials is a resetting rock bar 20 having a series of lugs 21, and also carrying slides 22, 23 and 24, each having a series of lugs movable with said slides axially of the 100 dials. Bar 20 may be rocked rearwardly from its normal position shown in Figs. 4, 5 and 6, to bring the lugs 21 thereof, and the lugs of slide 24 into the path of movement of stop pins arranged on the counting dials. Said bar is also 105 movable forwardly from its normal position, to bring other of the lugs 21, and the lugs 33, 39, 42, 45 and 48, of the slides 22 and 23, into the path of movement of stop pins on the accumulator dials. Bar 20 will be rocked first in the 110

one and then in the other direction, as above-noted upon rotation of crank 18, by the means hereinafter referred to, rotation of said crank also imparting one revolution to shaft 28, by means of the gearing 56, 57, the accumulator wheels mounted on this shaft being carried around therewith by frictional contact. When, therefore, the lugs of rock bar 20 are brought into the path of the numeral wheels the rotation of shaft 28 will bring the stop on the numeral wheels into contact with the lugs of the rock bar, and the numeral wheels will be held in the desired resetting position.

Fig. 3 illustrates the position of the parts, with slides 22 and 23 adjusted to reset the dials for the calculation of tax problems as follows:

Sub-total dials 29 have their pins 30 in the path of lugs 21 of rock bar 20, for clearing to 0. Between dials 34 and 40 any number of dials 20 may be provided, arranged to clear similarly to dials 29. Mills dial 31 (as shown) has a pin 32, in the path of lug 33 on slide 23, arranged for clearing to 5 during tax computations, so that a carry to the cents dial will occur upon an accumulation of five mills. Cents dial 34 has two sets of numerals upon its face, arranged side by side, set 35 comprising even figures only, arranged as shown in Fig. 7, and set 36 having the usual ten figures, running from 0 to 9. Set 35 is used during tax computations to indicate the nearest even cent. Both of these sets of figures are arranged about the dial with relation to the carry pin 37 so that said pin will pass through the cooperating carry gear, shown in dotted lines in Fig. 6, as the figures of either series change in the slight opening of the numeral wheel carriage from a registration of zero to a registration of the highest digit of said series, or vice versa. The gear shown in dotted lines in Fig. 6 may be a direct gearing connection from a lower to a higher order numeral wheel, or other delayed action carry mechanism may be employed, both of these types being well known, and both being illustrated, for example, in Patent 1,462,058, issued on July 17, 1923 to E. F. Britten, Jr., and entitled Carry mechanism for registers.

It is to be noted of the series of even figures, that the true zero is the figure located next to the 2, and opposite the 1 of series 36, to which true zero position the dial must be reset during tax computations. Therefore, the resetting position related to one series is out of line with the resetting position related to the other series, and separate stop pins 38 and 59 are provided on dial 34, pin 38 cooperating with lug 39 on slide 23, for clearing the special figures to 0. Grand total decimal dials 40 are provided with stops 41, lying in the path of lugs 42 on slide 23, for resetting to 0. Mills dial 43 (as shown) has stop 44 in the path of lug 45 of slide 23, for clearing to 5. Cents dial 46 has two sets of numerals, arranged in the same manner as described for dial 34, but is provided with five stops 47, any of which may engage lug 48 of slide 23 for resetting to a true figure corresponding to the even cent figure last accumulated in the dial. Tens of cents dial 49, which is similar to all of the dials located to the left thereof, will not contact with any lug, in the above-described setting of the slides, and the amounts accumulated on these dials will be retained as a grand total.

Starting from a reset position for every cent operation and assuming that three is accumulated on each of the dials 34 and 46, it will be

obvious that dial 34 will show an arbitrary registration of 4, and that dial 46 will also show an arbitrary registration greater by one than the true value. Also, it will be noted that the half cent dials 31 and 43 having previously been cleared to 5, instead of 0, further modification of the amount registered may be obtained. Thus, for example, a value of 29.8523, would be registered as 29.8673.

For the convenience of the operator in reading the numerals of the cent dials, movable shutters may be provided, a well-known arrangement whereby the figures of the series not being read will be obscured.

Fig. 4 illustrates a cam action, for moving rock bar 20 into the path of the stops on the dials in advance of the rotation of shaft 28, this being necessary because, if dial 46 is registering a true even figure, the stop must be in position for action to retain such true figure before the dial is rotated. When crank 18 is rotated in a clockwise direction (Fig. 4) shaft 50 is rotated thereby in the same direction, and a wall of cam surface 51, acting upon arm 52 rocks the same about stud 53, a lug 54 on said arm moving rock bar 20 forward about its studs 53 and 55 in advance of the action of mutilated gear 56 upon gear 57. In the reverse direction of movement of shaft 50, utilized in clearing the counting dials, by means of a second pair of gears similar to gears 56, 57, a wall of cam notch 51 will move arm 52 downwardly, and said arm will slide on stud 53 without any action on rock bar 20. Spring 58 holds arm 52 in engagement with cam notch 51.

For a normal operation, slide 23 is moved to the position shown in Fig. 2, moving lugs 33 and 39 into the path of stops 59 and 60, so that dials 31 and 34, as well as the other dials of the right hand group, will clear to 0. In this position lugs 42, 45 and 48 will not be in the path of the pins of dials 40, 43 and 46, and these dials will be reset or left undisturbed, according to the setting of slide 22. When slide 22 is positioned to clear the left hand dials, dials 43 and 46 will be cleared to 0, by means of the lugs 61 and clear pins 62.

Obviously if it were desired to construct a machine for even cent calculation only, dials 34 and 46 would have one set of numerals only, and the stop pins on the dials might be arranged in simpler form. The two sets of stop pins, one set active in one position of the cooperating lugs of the slides, and the other set active in another position of the slide, corresponds with the disclosure of application 379,948, hereinbefore referred to.

It is also obvious that the half cent dials 31 and 43 might be dispensed with, ordinary dials, clearing to zero, being employed in the mills order. This would give a computation of the odd cents to the next higher even cent.

As illustrative of the operation of the present invention to eliminate mental revision of sub-totals and the accumulation of errors in the grand total dials, the following example is given:

Rate of assessment \$21.79 per \$1000.00

Valuation	Assessment per former method	As corrected
\$1,370.00 1,200.00	\$29.8523 26.148	\$29.86 26.16
Total....	56.0003	56.02

This calculation was begun with the machine in the condition illustrated in Fig. 1, except that the grand total dials were set similarly to the sub-

total dials. The amounts on the keyboard were then transferred seven times to the totalizers; the carriage shifted to the right; the amounts transferred three times; the carriage shifted, and the 5 amounts transferred once, giving a multiplication by 137. Both series of dials now read 29.86. The carriage was then repositioned and the resetting mechanism operated, which, as will be evident from the foregoing description, would 10 bring the machine into the condition illustrated in Fig. 1. Multiplication by 1200 now gives the corrected or arbitrary registration 26.16 on the sub-total dials and 56.02 on the grand total dials.

I claim:

15 1. In a register having a shaft and dials mounted thereon; resetting means comprising projections on said dials, devices for rotating said shaft, a carrier movable toward said dials, and two laterally adjustable members mounted upon 20 said carrier, overlapping each other at their adjacent ends and provided with lugs formed in the overlapping and in the non-registering portions thereof and movable in the adjustment of the related member into or out of the path of movement of the dial projections.

2. In a register having dials; resetting means

including devices operable to reset a dial to the next lower one of a plurality of given registering positions and adapted for automatically selective action to leave said dial undisturbed when it stands in any one of said given positions.

3. In a register having a dial marked with a series of figures representing a plurality of true values and a plurality of arbitrary values; resetting means including devices operable to reset said dial to the nearest true value registering position.

4. In a register having sub-total dials including a dial marked with a series of figures representing a plurality of true values and a plurality of arbitrary values and grand total dials including a dial marked in conformity with said sub-total dial; resetting means including an operating member, devices operable thereby to reset said sub-total dial invariably to a single given registering position, and devices operable by said member to reset said grand total dial to the nearest true value registering position.
